US00D579315S

(12) **United States Design Patent**
Samhammer et al.

(10) **Patent No.:** **US D579,315 S**
(45) **Date of Patent:** **** Oct. 28, 2008**

(54) **LATCH**

(75) Inventors: **Christopher Samhammer**, Redmond, WA (US); **Richard K. Simms**, Redmond, WA (US); **Linsey K. Mallory**, Montesano, WA (US); **Patrick C. Moran**, Seattle, WA (US); **Ximena Rozo**, Seattle, WA (US); **Juliane B. Trummer**, Seattle, WA (US)

(73) Assignee: **The Boeing Company**, Chicago, IL (US)

(**) Term: **14 Years**

(21) Appl. No.: **29/297,041**

(22) Filed: **Nov. 1, 2007**

(57) **CLAIM**

The ornamental design for a latch, as shown and described.

DESCRIPTION

FIG. 1 is a perspective view of a latch of the present invention; FIG. 2 is a front elevational view thereof;

FIG. 3 is a top view thereof;

FIG. 4 is a right side view thereof;

FIG. 5 is a perspective view of a second embodiment of a latch of the present invention; and,

FIG. 6 is a front elevational view thereof.

The broken line showing is included for the purpose of illustrating and forms no part of the claimed design.
